R. J. FRY.

MACHINE FOR SHAPING PREPARED BLANKS IN THE MANUFACTURE OF HORSESHOES.

APPLICATION FILED APR. 15, 1912.

1,126,626.

Patented Jan. 26, 1915.

UNITED STATES PATENT OFFICE.

RICHARD JOHN FRY, OF KENSINGTON, VICTORIA, AUSTRALIA.

MACHINE FOR SHAPING PREPARED BLANKS IN THE MANUFACTURE OF HORSESHOES.

1,126,626.

Specification of Letters Patent.

Patented Jan. 26, 1915.

Application filed April 15, 1912. Serial No. 690,733.

To all whom it may concern:

Be it known that I, RICHARD JOHN FRY, a subject of the King of Great Britain, residing at 70 Hardiman street, Kensington, 5 in the State of Victoria, Commonwealth of Australia, manufacturer, have invented certain new and useful Improvements in Machines for Shaping Prepared Blanks in the Manufacture of Horseshoes, of which the following is a specification.

The object of this invention is to provide exceedingly simple and useful improvements in machines for shaping prepared blanks in the manufacture of horse-shoes in which a heated blank is placed between two stop or abutment pins and an inside forming die movably mounted on a table. A forward movement is given to the said die by a pitman rod and eccentric to bend the blank and 15 carry it into the sphere of operations of two outside forming dies. The said dies are mounted on pins passing vertically through the table and the said pins are provided with arms against which a sliding block supporting the said die is adapted to strike to force the outside forming dies against the bent blank and squeeze the heel portions of the same tightly on the said inside forming die. Directly the blank has been given the desired 20 shape a press or hammer is operated by a cam and rocking beam to flatten and seat the formed shoe. During the time the hammer is bearing on the formed shoe the continued operation of the eccentric is returning the 25 pitman rod to its original position and in order to permit of it doing this a loose connection is effected between the outer end of said rod and the block to which the inside forming die is affixed.

40 In order that the invention may be readily understood reference will now be had to the accompanying sheet of explanatory drawings, wherein:—

Figure 1 is a view in side elevation of a 45 horse-shoe bending machine fitted with some of the improvements comprised in the present invention and showing part broken away to illustrate the operative parts thereof. Fig. 2 is a view in plan of Fig. 1. Figs. 3, 4, 50 5 and 5^a are views of details in the construction of the improvements shown in Figs. 1 and 2. Fig. 6 is a view of a modification in the construction of the pitman rod connecting the forming die to its operating eccentric. Figs. 7 and 8 are views in plan 55 of part of the machine showing modifica-

tions in the means devised for bending the prepared blanks around an inside forming die. Fig. 9 is a view illustrating details of the modification shown in the two preceding 60 figures. Fig. 10 is a view in sectional elevation showing modifications in the means employed to flatten formed horse-shoes. Fig. 11 is a diagrammatic view showing modifications in the arrangement of the operative 65 parts of the machine. Fig. 12 is a view in sectional plan of part of Fig. 1 taken on the dotted line I—I. Figs. 13 and 14 are views of details in the construction of the invention hereinafter described.

Throughout these drawings like characters of reference have been employed to indicate similar parts in the different views and the numeral 1 designates the machine framing which is preferably cast as shown 70 and is supported on a suitable bed or stand 75 2. Projecting forwardly from the front part of the framing 1 is a bifurcated extension 3, the upper surface of which forms a table and is made perfectly flat to insure a 80 free movement thereover of a sliding member or plate 4. This sliding member 4 is detachably secured by bolts 5 to a block 6 which is movably mounted within the bifurcated extension 3 and is actuated by a pitman 7 and an eccentric 8, the latter being mounted on a shaft 9 disposed crosswise in the rear of the framing 1. This said shaft 9 receives its motion from a driving shaft 10 fitted with belt and fly wheels 11 and 12, 85 90 respectively, or in any other approved way. Fitted to the shaft 9, one on each side of the eccentric 8, are two eccentrics 13 which are encircled by the lower ends of links 14 having their upper ends forming pivotal 95 connections with the rear end of a rocking beam 15. The said rocking beam 15 is oscillatorily mounted on a cross shaft 16 and its front end projects beyond the front of the framing and pivotally supports a hammer 17. The front of the framing over which the hammer 17 is reciprocated by the oscillatory motion of the beam 15 may be made at right angles to the surface of the bifurcated extension 3, as shown in Fig. 1, 100 105 or it may be made at an obtuse angle thereto, as shown in Fig. 11. If preferred, the said hammer may be arranged to operate at any angle other than those illustrated in the drawings and the operative parts of the 110 machine can be made to correspond with the modified construction of framing. The

2

wheel of the gear employed to transmit motion to the shaft 9 from the driving shaft 10 is normally free to run on the first mentioned shaft and this said wheel can be 5 placed in a fixed relationship to said shaft by means of clutch and lever mechanism of ordinary design. The said clutch lever may be actuated by means of a foot lever to throw the clutch in gear and this latter is 10 adapted to be automatically thrown out of gear again upon the completion of a revolution of the shaft 9. The sliding member 4 is adapted to fit closely on top of the bifurcated extension 3 and formed integrally 15 therewith and projecting upwardly therefrom is or are one or more inside forming dies 18 around which the prepared blanks are bent to form horse-shoes. The inside forming die is preferably provided with a 20 small beveled ledge 19 near its lower edge to form a seating on the inner edge of the horse-shoes when the same are pressed downwardly on the said die by the operation of the flattening hammer. It will be 25 obvious that the seating of the shoes may be formed by having a beveled crown on the hammer or press 17 and by bending the shoe blanks with the fullered side downward.

The forward end of the pitman rod passes 30 through a tapered hole 20 (indicated by dotted lines in Fig. 3) and is provided on its front end with a thick washer or block 21 and nut 22. The inner face of the washer or block 21 is rounded to form a knuckle bearing in a similarly shaped recess 23 formed in the outer end of the block 6. A spiral compression spring 24 is fitted over the pitman rod 7 and bears at one end 35 against a washer 25 abutting against the rear of the block 6 and at the opposite end against a collar 26 or the like adjustably 40 fitted to the said pitman rod. This form of construction will readily permit of the pitman rod moving to its normal position independently of the inside forming die and 45 when the pressure of the flattening hammer is removed from the shoe the said die will be instantly propelled to its original position by the action of the spring on the pitman rod.

A modification in the construction of the pitman rod 7 may be effected by forming it in two parts (see Fig. 6) and connecting them by a form of knuckle joint 27. The 50 forward end of the pitman rod passes through the said block 6 and is provided with a nut 22 and washer 21, as before described, while the rear end is connected to the eccentric 8 for operating the same. The 55 said joint is made to buckle downwardly at the center or jointed part, as shown in dotted lines, when the pressure of the hammer 17 prevents the inside forming die 18 moving back to its original position. Directly the 60 pressure of the hammer 17 is released from

the shoe on the forming die 18 the sliding block 6 and its attached parts are drawn to their original positions by means of a weight 28 or spring (not shown). The said weight 28 is connected to a lug 29 on the block 6 70 by means of a flexible member 30 and this latter passes over a pulley or roller 31 mounted on the extension 3 of the machine framing.

Supported transversely across the bifurcated extension 3 is a bar 32, the ends of which are adjustably supported on vertical pins 33 projecting upwardly from the surface of the said extension. The height of this cross bar 32 may be adjusted by means 80 of nuts 34 or the like and secured adjustably to each side of the center of said bar is an abutment pin 35 against which the prepared blanks 36 are adapted to bear when in the act of being bent. These abutment pins 35 85 are so placed that the blanks are bent closely around the points of the forming dies 18 leaving the heel portions thereof projecting toward the front of the machine in the form of a staple. Any approved form of guide or guides can be used to correctly locate the blanks on the table so that they may be bent as desired.

The heel parts of the bent blanks are 90 pressed inwardly against the forming dies 18 by means of laterally operating tools 37 having their inner faces shaped to correspond to the outside of a formed shoe. These tools 37 are formed at an approved point in their lengths with bosses 38 which 100 are adapted to fit over studs or pins 39 projecting upwardly from the forward ends of levers 40 fitted rigidly to shafts or spindles 41 located one on each side of the reciprocating member 4 and at right angles thereto. 105 The said levers 40 can be made in the form of bell-cranks, as shown in the drawings, or they may be given any other approved formation. These shafts or spindles 41 are 110 oscillatorily mounted in the machine framing and are provided on their opposite and lower ends with inwardly projecting arms 42—see Fig. 12—with which the lower part of the block 6 is adapted to come into contact when near the limit of its travel in a 115 rearward direction. When the block 6 comes into contact with the inwardly projecting arms 42 they are forced rearwardly and operate the spindles 41 carrying the bell cranks 40 with the adjustable heel shaping 120 tools 37 inwardly and pressing the heel parts of the shoes on the inside forming die 18. Directly the sliding member 4 commences to move forwardly on its return stroke the tools 37 are forced outwardly to 125 their normal positions and the spindles 41 also moved back to their original positions. The outer ends of the heel forming tools 37 are formed with bosses 43 or the like to 130 which may be fitted eyebolts 44 adapted to

receive the bent ends of connecting rods 45 having their rear ends adjustably fitted to brackets 46 or the like fitted to or forming part of the framing of the machine. The 5 outer ends of the tools 37 may also be provided with one or more holes 47 into which the forward ends of the connecting rods 45 may be inserted when it is desired to alter the operative positions of said tools. The 10 rear ends of the connecting rods 45 may be screwed and provided with adjustment nuts 48 or the position of these said rods relatively with the brackets 46 may be adjusted by other approved or well known means. 15 The adjustment of the said rods 45 permits of the shaped ends of the tools 37 being made to press more or less hard on the heel or on the side parts of a shoe, as preferred. The engagements between the connecting 20 rods 45 and the brackets 46 must be sufficiently loose to permit of the former having a free pivotal movement to insure a correct working of the tools 37. The ends of the bell crank levers 40 opposite to those supporting the tools 37 are provided with screws 49 or other approved means for effecting an adjustment of the said levers relatively with the position of the movable dies 18 at any part of their travel. The 25 tools 37 may be readily detached from the bell crank levers 40 and others of a different size or shape may be quickly substituted therefor while the latter may be arranged in any approved way to control the movement 30 of the tools in a lateral direction and oppositely to each other.

In lieu of locating the stop or abutment pins 35 fixedly on top of the table they may be affixed to the inner ends of two oppositely 40 bent levers 50 which may be oscillatorily pivoted at a suitable point in their lengths to pins, studs or the like 51 on the table. Said abutment pins 35 can be provided with rollers to reduce friction and to facilitate 45 the operation of the machine. The inner ends of said levers 50 are arranged to move about the plate 4 to which the inside forming dies 18 are affixed, while their outer ends are provided with pins or rollers 52 adapted 50 to bear on the outer end of the said plate. The said plate 4 is provided on its upper surface with the inside forming dies 18 one for shaping front shoes and the other for shaping hind shoes of a like size. This 55 plate 4 is given rounded ends and when it is in its outermost position the rollers on the outer ends of the levers 50 bear against or near the ends of the straight sides 53 of the plate or at that point where the curve commences—see Fig. 7. When the plate 4 and outer ends of the levers 50 are in the positions stated a heated blank 36 can be placed against the pins 35 on the opposite ends of the levers and these said pins will be sufficiently far apart to allow of the said blank

being bent by the movement of the dies 18. When the inner die 18 is forced inwardly against the blank 36 the latter is bent into the form of a staple and during this operation the inner ends of the levers 50 are 70 moved outwardly while the outer ends thereof move inwardly and follow the curvature of that end of the plate. The die 18 as before mentioned moves inwardly until it is between the shaped ends of the tools 37 75 which then operate as hereinbefore described to shape the side and heel portions of the shoe.

The pins 35 on the levers 50 may be made adjustable while the levers themselves can 80 be detachably affixed to the table to permit of them being quickly removed and replaced by others of a different size or for performing different kinds of work. The levers 50 are pivoted preferably midway between the 85 pins 35 and 52 and as their inner ends move outwardly to follow the contour of the shoe being formed the outer ends move inwardly and follow a curve similar to that formed by the periphery of the formed shoe but 90 made inversely thereto. Thus, the outer ends of the levers 50 bearing against the inward curves on the side of the plate 4 causes the abutment pins 35 on the inner ends of the said levers to move outwardly 95 to give to the blank its correct shape. It is not absolutely essential to the correct working of the machine that the levers 50 should be pivoted at their centers as they can be pivoted at other preferred points and the 100 curves on the side of the plate 4 may be altered to correspond therewith, as will be well understood.

The plate 4 may be shaped as illustrated in the drawings so as to be used at one end 105 for shaping front shoes and at the opposite end for manufacturing hind shoes of the same set.

If preferred, the shoe may be formed completely by means of the levers 50 and 110 the tools 37 for shaping the heel and side parts can be dispensed with. In order to accomplish this object the outer end of the plate 4 is shaped as shown in Fig. 13 of the drawings with two oppositely disposed 115 and inwardly curved recesses 53^a around which the pins or rollers 52 on the outer ends of the levers 50 travel to make the abutment pins 35 bend the blanks into complete horse-shoes. These recesses 53^a are 120 identical in shape to the outer peripheries of the finished shoe when the levers 50 are pivoted centrally.

In order to permit of the plate 4—shown in Figs. 13 and 14—being used to complete 125 the bending processes as above described it may be formed at each end with a lug 54 which is adapted to fit within a recess 55 formed in a detachable piece 56. The said detachable piece 56 can be retained fixedly 130

on the outer end of the plate 4 by means of a bolt or set screw 57 or by any other approved means. When it is desired to reverse the plate to form other shoes to complete the sets being manufactured the said piece 56 is detached and a similarly shaped piece (not shown) is fitted to the opposite end of the plate which will now be placed near the front of the machine. It will be obvious that the said pieces 56 may be of another shape than that shown and that said plates may be formed with a single die 18 on its upper surface in which case the piece 56 may be formed integrally with the outer end of said plate.

Instead of employing a hammer constructed as illustrated in Figs. 1 and 2 to flatten the formed shoes a hinged block 58 (see Fig. 10) may be used and operated by the rocking beam 15. This block is made perfectly flat on its underside and its forward part is hinged on a transverse spindle 59 the ends of which are supported in lugs or standards 60 formed on the table of the machine. The top of the said block 58 is connected to the projecting or forward end of the rocking beam 15 by means of links 61 or the like. If preferred, the said hinged block 58 may be provided on its top side with a jaw in which the projecting end of the rocking beam 15 can be pivoted in an approved way.

Various slight and immaterial modifications may be made in the construction and arrangement of the parts of the invention as illustrated in the drawing without departing from the scope of the following claiming clauses.

What I do claim is:—

1. In a machine of the class described, the combination with a flattening and seating press or hammer, of a forming die, a pitman rod, an eccentric upon which one end of the pitman rod is mounted, a slidably mounted block supporting said die and detachably connected to the forward end of said pitman rod and by which it is actuated, a washer or block on the end of the pitman rod forming a knuckle bearing on the front of the sliding block, a nut on said pitman rod for adjusting the position of the inside forming die, and a spring for keeping the sliding block normally at the end of the pitman rod, substantially as described and for the purposes set forth.

2. In a machine of the class described, the combination with a flattening and seating press or hammer, of an inside forming die, a slidably mounted block supporting said die, an oscillatorily mounted spindle at each side of said die and arranged at right angles thereto, inwardly projecting arms on one end of said spindles with which the block co-operates to oscillate the spindles, levers on the opposite ends of said spindles, and shap-

ing tools pivotally carried by said levers to shape the heels of the shoes, substantially as described and for the purposes set forth.

3. In a machine of the class described, the combination with a flattening and seating press or hammer, of a forming die, a slidably mounted block upon which said die is supported, an oscillatory spindle at each side of said die and arranged at right angles thereto, inwardly projecting arms on one end of said spindles with which the sliding block co-operates to oscillate the spindles, levers on the opposite ends of said spindles, a shaping tool pivotally mounted on one arm of each lever, and adjusting means connected to the other arm of said levers, substantially as and for the purpose specified.

4. In a machine of the class described, the combination with a flattening and seating press or hammer, of a forming die, a slidably mounted block upon which said die is supported, an oscillatory spindle at each side of said die and arranged at right angles thereto, inwardly projecting arms on one end of said spindles, levers on the opposite ends of said spindles with which the sliding block co-operates to oscillate the spindles, a shaping tool pivotally mounted on one arm of each lever, adjusting screws connected to the other arm of said levers, and adjustable links connecting the outer ends of the shaping tools to the machine framing, substantially as and for the purpose specified.

5. In a machine of the class described, the combination of a flattening and seating press or hammer, a forming die, a slidably mounted block upon which said die is supported, means to reciprocate the block, an oscillating lever at each side of the path of movement of the die with which the block co-operates to impart oscillating movement thereto, and shaping tools pivotally carried by said levers or arms, substantially as and for the purpose specified.

6. In a machine of the class described, the combination of a flattening and seating press or hammer, a forming die, a slidably mounted block upon which said die is supported, means to reciprocate the block, an oscillating lever on each side of the path of movement of the die with which the block co-operates to oscillate the lever, shaping tools pivotally carried by said levers or arms to engage with and shape the heels of the shoe, and means to adjust the positions of said tools, substantially as and for the purpose specified.

7. In a machine of the class described, the combination of a flattening and seating press or hammer, a slidably mounted plate having portions of its sides adjacent its outer ends straight and parallel with each other and portions curved inwardly from the inner ends of the straight portions, a forming die supported by the plate, levers at opposite sides of and oscillated by the plate, and

forming tools pivotally carried by said levers between which the die is adapted to pass, to bear against and shape the blank to the die.

5 8. In a machine of the class described, the combination with a flattening and seating press or hammer, of a reciprocable plate having portions of its sides straight and parallel with each other and portions curving inwardly from the ends of the straight portions, forming dies supported on said plate, a bell-crank lever mounted at each side of said plate, abutments projecting from the inner ends of said levers, the outer ends 10 of said levers being adapted to bear against and follow the sides of the plate, substantially as and for the purpose specified.

9. In a machine of the class described, the combination with a flattening and seating

press or hammer, of a reciprocable die carrying plate having portions of its side straight and parallel with each other and portions curved inwardly from the straight portions adjacent the ends, detachable end pieces for said plate having portions of its sides curved inwardly to meet the curved portions of the plate, and pivotally supported tools to shape the blank around the die, said tools having portions to engage with the plate and its detachable piece to cause the tools to bear against and form the blank to the shape of the die. 20 25 30

In witness whereof I have signed this specification in the presence of two witnesses.
